INVENTOR

Fred E. Moore

UNITED STATES PATENT OFFICE

2,017,321

CHAIR BED

Fred E. Moore, Los Angeles, Calif.

Application July 6, 1931, Serial No. 548,880

4 Claims. (Cl. 155—49)

My invention relates to chairs of the class embodying structure effective of modification into a bed, chaise longue or the like, and more particularly involves improvements, as set forth herein, emulating the structures described and claimed in the United States patent granted to me July 5, 1927, No. 1,636,551 and the pending application filed April 2, 1928, Serial Number 266,662.

10 The primary object of my invention is to provide, in a chair, or the like, of the character described, means automatically interfunctional between the main frame and the swing-back to provide automatic adjustment between the main frame and the swing-back by manual movement solely of the swing-back. My improved position stop does not require the use of auxiliary means such as latches, releases and such devices; that must be manually functioned coordinately with 15 the disposed position relation of the swing-back to the main frame, and thus provides means of automatically securing the adjustable positions of the swing-back relative to the correlated members of the chair: the adjustable seat with the 20 stool as an adjunct.

Another object of my invention is to provide the means, the resilient adjustable unit closure member or unit bottom, whereby the ensemble adjustment of the members forming the extensible seat of the chair—the unit filler or cushion and the stool—are arranged and maintained in 25 positions affording a plurality of dispositions for the comfort of the occupant when the chair is adjusted for a lounging attitude.

30 A further object is to provide means, assuring the modification adjustments characterized as above defined, adaptable for incorporation in all period designs of chairs without detracting from the appearance or modifying the general design 35 of the period chair, or the like, embodying the invention.

Another object is to provide as one of the modifications of adjustment of the filler cushion and the extension stool, an adjustable position of these 40 members wherein they are coactive to form a more than ordinarily amplified double inclined support, apex upward, for the support of the lower limbs of the occupant, flexed to a marked degree, yet sustained their entire length in a comfortably resting position.

With the above and other objects in view the invention subsists in the novel construction and combination of parts hereinafter described, illustrated in the accompanying drawings, and set forth in the claims hereunto appended, it being

understood that various changes in the form, proportion, size and minor details of construction within the scope of the claims may be resorted to without departing from the spirit or sacrificing any of the advantages of the invention. 5

In the drawings:

Figure 1 is a side elevation of the device depicting the relation of the members when functioning as a chair.

Figure 2 is a side elevation of the device depicting the disposition relation of members when functioning as a couch. 10

Figure 3 is a side elevation of the device depicting a disposition of the members in a novel manner forming a modified chaise longue. 15

Figure 4 is a side elevation, part sectional, of one of the swing-back connectors and position stops.

Figure 5 is a part sectional view on line 5—5 of Figure 4. 20

Figure 6 is a fragmentary schematic detail depicting the "automatic" cycle of relation and interoperative action of one unit of the swing-back connector and the resilient detent or deflector.

Figure 7 is a section on line 7—7 of Figure 6. 25

Figure 8 is a detail plan view of the unit adjustable resilient bottom of the chair and a detached fragmentary portion of the stool.

Figure 9 is a longitudinal part-section on line 9—9 of Figure 8, showing an elevated, or second 30 position, disposition of the unit adjustable bottom and the correlated stool.

Figure 10 is a detail view of one of the escutcheon-like guide plates with parts conserving the functions of adjustability of the unit bottom as 35 set stop means.

Figure 11 is a view similar to Figure 7 showing the adaptation of two resilient detent members to the position stop.

Figure 12 is a fragmentary schematic view 40 of a position stop and the telltale therefore.

As a chair bed, my invention comprises four main members forming an ensemble wherein the position relation of these members to each other and the means whereby these relations are attained and maintained constitute the subject matter of my invention. 45

Referring to the drawings in detail, the device consists of the main frame A, the swing-back B, the extension or extensible stool C and the filler 50 or cushion D.

The main frame A consists of the side frames 1 embodying the arms 2 united to the frame 1 by the back post 3 and maintained in desired spaced relation by the rear spreader 4 and the 55

front spreader 5 to which are secured the legs 6. The respective parts of the ensemble are united by usual methods and upholstered as desired.

The swing-back B, constructed as a unit, consists of the substantially rectangular frame 7 of desired form finished or upholstered in the usual manner requiring no further description. In the design of swing-back B, depicted, the lower portion 8 of the frame 7 with upholstery affixed, is constructed to fit between the back posts 3 of the main frame A. The upper portion 9 of the swing-back is widened to overlap the upper extremity of the back posts 3 and junction of the arms 2 and form a flush or extended finish of the chair back relative to the main frame A. The lower extremity of the swing-back B is opposingly trunnioned to swing on the pins 10 secured in the frame 7, in any suitable manner, and adapted to rotate in holes provided in the back post 3 and in aligned holes in the fixed members of the swing-back position stops E, positioned on each side of the main frame A, Figures 4, 5 and 8.

The automatic position stop E consists of the stop means proper 11, and a connector 12, illustrated in adaptable form Figures 4 and 5. The term "automatic" specifically defines a position stop interactively operative between the main frame member and the swing-back member to obtain and maintain relative adjustable positions of these members by movement solely of the swing-back member.

As the automatic position stops, one on each side of the swing-back, are identical, a description of the one will serve for the other.

The position stop consists of two coacting members, it being obvious that either may be constituted the fixed member, and that a single notched slot member mounting the related parts will function similarly to the two parallel plate construction shown.

As illustrated the fixed member 11 consists of two segmental plates 13-13 maintained in parallel spaced relation by stay rivets 14, Figure 4, and others designated later. The segmental plates 13 are provided at one apex with a hole 15 adapted to receive the trunnion pins 10 previously described. The plates 13-13, as a unit, one on each side of the main frame 1 are secured thereto in aligned opposed position, by suitable means, as screws in the holes 16. Centered on the hole 15 the plates 13-13 are provided with the arcuate slots 17 having the desired number of stop notches 18 in the one edge thereof. Opposite each of the plurality of stop notches 18, is positioned the resilient detent or deflector 19 purposed to function to, in the one instance of movement of the connector 12; shunt the connector into respective stop notches 18, and in another instance of movement of the connector; "by-pass" the connector relative to respective notches 18. The functioning of the detents 19 relative to the respective stop notches 18 depends upon the amplitude of the movement solely of the connector 12 and a property imparted to the connector.

This property of the connector 12 subsists in causing the guide means, as the pin 20 integral with the connector and engaging the slot 17, to be maintained in forced contact with the side of the slot 17 opposite the notches 18.

The resilient detent or deflector 19 is illustrated as made of spring wire formed as a substantially one and one half turn spiral spring coil 21, the one end thereof prolonged as a tangential extension 22 and the other end bent to a semi-radial short extension 23 which, in order to pro-

vide a substantial wearing surface is bent back or doubled on itself a short distance in a plane parallel to the axis of the spiral coil portion 21. The coil portion 21 of the detents 19 is rotatably mounted between the plates 13-13 on the stay rivets 24 positioned opposite the notches 18, relative thereto and the slot 17, to function therewith and with the connector 12, as later described.

The connector 12 of suitable material, as a steel bar, and of the form desired, illustrated as a 10 straight bar, is mounted at one end forcibly rotatable (on means securing this end to the swing-back B) in a plane parallel and between the plates 13-13 of member 11. As illustrated the forcibly rotatable functions above defined are obtained by providing the connector with the bore 27 through which a tight fitting screw 28 extends into the plate 29 which is secured to the swing-back frame work 8, by screws in the holes 30. To provide additional friction and conserve the function of forcible rotation of the connector 12 on the pivot 28 a resilient rub plate 31 interacts between the plate 29 and the connector 12. The end of the connector 12 engaged between the plates 13-13, and forcibly movable in the plane thereof, is provided with guide means engaging the slot 17, as the pin 20 adaptable also to engage the stop notches 18. The extremity of the connector 12, surrounding the pin 20, has a perimeter, "hook-shaped" in form, the angular surfaces thereof facing the detents 19 and coactive therewith.

Attention is directed to Figure 6 illustrating a cycle of functions of the coactive parts; the stop notched slot, the resilient detent and the connector. It is apparent that, in the structure shown, the resilient detent is forced to exercise the quality of resiliency only within fixed limits determined by the stop pins 32 engaging the extension 22 of the detent otherwise free to oscillate on the stay rivet 24. The several illustrations of Figure 6 are designated as b, c, d and e and so referred to. In "b" the guide pin 20 of the connector 12 (hereinafter referred to simply as the connector) engages the stop notch 18 maintaining a stop position of the connector in a direction toward the closed end of the notch 18. Movement of the connector, in the direction of the arrow or open end of the notch causes it to slide out of the notch 18 into the slot 17.

For all relative positions of the connector and the detent the coactive functions are positive and independent of the action of gravity although positions of the detent resulting from gravitational action do not alter the continuity of positive coaction of the parts for the following reason. As illustrated in "b" the dotted line position of the detent is that which would result from the weight of the extension 22 rotating the detent on the stay rivet 24. This position of the detent is, however, that shown in "c" as requisite to perform the function of by-passing the connector as shown in positions relative thereto from "b" to "c". In "d" the dotted line position of the detent, gravitationally effected, is the position requisite to shunt the connector, shown relative thereto in the dotted and full line positions.

The positive feature of coaction of the detent and connector resides in the positioning of parts such that the faces of the point of the "hook" of the connector engages the detent when moved toward it from any one of the three paths of approach of the connector, determined by the two branches of the slot 17 relative to the notch 18.

To "by-pass" a position stop notch 18 (shown engaged in "b") the connector, and connected 75

- parts as the swing-back B, is first moved in the direction of the arrow in "b" to the position in "c". As above described the guide (as the pin 20) of the connector is maintained in forced contact, 5 when so positioned, with the edge of the slot 17 opposite the notches 18. In moving the connector out of engagement with the notch 18 the guide (as the pin 20) of the connector is, as above described, forcefully positioned and maintained in 10 a position out of the path of engagement of the notch 18, as in "c", and a movement of the connector in the direction of the arrow (the reverse of that in "b") "by-passes" the connector with respect to the stop notch. 15 As illustrated and described the by-pass movement of the connector is effected by first moving the connector from a stop notch position, as at "b", to that of "c" then moving the connector in a direction the reverse of the first movement. 20 The shunting or notch engaging movement of the connector is effected as follows. In the illustrations "c" and "d" it is evident that movement of the connector toward the detent; as guided by the pin 20 in the slot 17 which maintains the 25 respective faces of the "hook" in a path of contact with the resilient detent extension 23, will cause the detent to exercise the function of resiliency without limits effected by the stop pins 32. It is evident that continuation of the movement 30 of the connector, disengaging the notch as from "b" to "c", causes the detent to function resiliently and pass the "hook" to the dotted position in "d", and that a reversal of movement causes the detent to exercise the function of resiliency, illustrated in "e", and shunt the connector to enter engagement with the stop notch 18. Continued movement of the connector (as in "e") to engagement with the heel of 35 the notch releases the detent, and the relation of parts, the detent and connector, becomes that illustrated in "b" completing a cycle of operations designed as by-passing or shunting the connector. 40 It is apparent that in the event of a movement of the connector, through a successive number of stop notch positions, in a direction toward the heel of the stop notches the successive detents inherently shunt the connector into respective 45 notches, out of which they are disengaged by operation in the manner described as by-passing. It is further apparent that in movement of the connector in the reverse direction, away from the heel of the notches, the movement is not one of "steps" but continuous, the connector "hook" simply "snapping" past the detents. 50 From the foregoing description of the automatic position stop it is evident that the connector 12, the one end thereof secured as described to the swing-back B, is functioned by: 55 movement solely of the swing-back. The manner and amplitude of movement of the connector causes it to either engage or be released from a position stop (as desired) for adjustment of the swing-back in any one of the positions provided, as illustrated by dotted line positions w, x and y, Figure 2. Position z, as that of the swing-back forming a couch, is obtained by by-passing the connector out of the stop position y (the "last" of the series of stop notches 18 as provided in the 60 illustrating member 11) and the couch forming position of the connector and swing-back is maintained by the guide pin 20 engaging the termination of the slot 17, as illustrated in Figure 2. 65 The resilient adjustable unit closure member or 70 unit adjustable bottom 33 consists of a frame 34, Figure 8, of suitable material as angle iron, adapted to fit between the sides 35 of the main frame A, Figure 8. The frame 34 is provided with a suitable resilient "seat" structure 36 as 75 coil springs and connecting links, well known in the art, and requiring no further description. The unit adjustable bottom 33 is adapted to sustain, when the stool is extended, the cushion or filler D in any one of a plurality of positions 10 desired. The bottom 33 is provided with guides (as the lug pins 37 and 38 Figures 8 and 9) that engage set stop means secured to the main frame A. The lug pins 37 and 38 project laterally into the slots 39 and 40 provided with the notches 41 15 and 42-43 respectively of the escutcheon-like guide plates 44 and 45. These plates—as set stop means—are secured (by suitable means as screws in the holes 46) to the inside of the members 35 of the main frame in opposed aligned 20 position with the slots 39 and 40 in a vertical position. The slot and notch position of the plates 44 and 45, Figures 2, 3 and 10, is "upset" to form a recess 47 to accommodate movement of 25 the head of the guide pins, as pin 37, without recourse to grooving the side members 35. The unit adjustable bottom 33 may be manually positioned in any one of a plurality of adjustment positions illustrated as any one of three 30 set stop positions, Figures 1, 2, 3 and 9. In Figure 1, the bottom 33 is positioned with the guide pins 37 and 38 sustained by the bottom of the slots 39 and 40 and when so adjusted forms, with the superimposed extensions stool C and the filler 35 D, a conventional chair seat. In Figures 2 and 9, the set stop position of the bottom 33 is that adaptable to form; in conjunction with the filler D, the extensible stool C and the swing-back B, a chair bed or chaise longue. In Figure 3, the set 40 stop position of the bottom 33 forms, in conjunction with the extension stool C a chaise longue seat of novel form for the purpose described. It is evident that the set stop positions of the unit bottom 33, Figures 2, 3 and 9, are obtained 45 by manually withdrawing the extension stool C, carrying the filler D, then grasping the seat member 36 and raising and positioning the bottom 33 with the guide pins 37 and 38 engaging the stop notches of the position desired. 50 The unit upholstered slideably extensible member C is termed a stool as designative of a two-fold utilization: a seat, when in the retracted position, and a support for the feet of the occupant when extended. The unit stool C is complete in itself requiring no complementary adjuncts, as cushions, to form a comfortable upholstered support for the lower limbs of the occupant, when the stool is extended. The extension stool C consists of a frame, upholstered as 55 60 a unit, adapted: to fit between the sides 35 of the main frame A, and to be manually extensible and retractile therein. The stool C is further adapted to slide over the unit bottom 33, and to be supported thereby in each of the relative positions 65 of the unit bottom and the concomitantly disposed stool positions. The stool C is provided with legs 48 and the extension of the stool, when drawn out of the main frame, is limited by the webbing straps 49, 70 Figures 8 and 9. The one extremity of the straps 48 is secured to the frame of the stool, as by tacking, the other being secured, as by the stitched loop 50, to the rear bar of the frame 34. In the retracted position of the stool the webbing 75

members 49 fold upon themselves as shown in Figure 1. In the extended positions of the stool the "front" is supported by the legs 48 and the "rear" thereof rests upon and is supported by the front portion of the unit adjustable bottom 33. Additional security, as a supporting feature, is obtained by the projecting lugs 51. As the retracted position of the stool C is substantially horizontal (Figure 1) and the length of the legs 48 proportional to this position, it is apparent that, in consequence of the "rear" of the stool—when extended—being supported by the unit adjustable bottom 33, any elevation of the bottom 33 will tilt the stool in a corresponding degree. By this means the coincined positions of the unit adjustable bottom 33 and the stool C, with the adjunctive filler D, are obtained to form the several positions of a chaise longue seat member.

As a method of construction prolonging the usefulness of the swing-back position stop, two of the resilient detent members 19 are mounted side by side on the stay rivets 24, Figure 11. The pair of detents function in the same manner as described for the one detent 19 shown in the analogous view, Figure 7.

It is apparent that the movement of the swing-back B; effecting movement of the connector 12 to approximately the position shown in Figure 6, "c", conserves the function of "by-passing" and that the requisite movement is one of degree as to amplitude. In practice this movement has been found readily obtainable, more especially as the resilient detent offers resistance to movement of the connector past that of maximum degree Figure 6, "c" effecting the by-passing operation.

To provide additional means affording the operator supplemental consciousness of the relation of parts, effecting the by-passing function, the telltale 52, Figure 12, is provided. As the telltale for each of the position stop notches is a duplicate of the others a description of one will serve for all. The telltale 52 consists of a resilient member as a flat bar spring one end thereof fixedly secured, as by the rivets 53, to the position stop member 11. The free end 54 is V-shaped cross sectionally and is positioned to engage, press upon and interrupt movement of the head 55 of the connector guide pin 20 when the guide has reached the correct position (with relation to respective stop notches and detents Figure 6, "c") for by-passing the connector. The resiliency of the telltale is proportioned to offer perceptible interceptive resistance to the passage of the head 55 of the pin 20, but not such a resistance as will prevent additionally forceful effort (applied to the connector) from entirely passing the

head of the pin 20, in either direction, to other positions of a movement cycle.

I claim:

1. In a chair, a main frame, a swing-back adjustably connected to the main frame, a vertically adjustable bottom in the main frame, means adapted to support the adjustable bottom in any one of a plurality of positions, and a movable stool overlying said adjustable bottom and supported thereby in the retracted position and extending outwardly from said chair when in the extended position, the inner end of said stool being supported by said adjustable bottom.

2. In a chair, a main frame, a vertically adjustable bottom in the main frame, means adapted to support the adjustable bottom in any one of a plurality of positions, a longitudinally movable stool having legs at its forward end and supported at all times by said adjustable bottom at its rearward end, and a cushion adapted to lie on said stool when said stool overlies said adjustable bottom or on said adjustable bottom when said stool is in the extended position.

3. In a chair, a main frame, a vertically adjustable bottom in the main frame, means on said main frame adapted to guide said adjustable bottom and support it in any one of a plurality of positions, a longitudinally slideable member having legs at its forward end said member overlying said adjustable bottom and supported thereby when in the retracted position, means limiting the forward movement of said slideable member to the extended position, said adjustable bottom forming the support for the rear end of said slideable member and a filler cushion adapted to fit on top of said slideable member when it is in the retracted position and to fit on said adjustable bottom when said slideable member is in the extended position.

4. In a chair, a main frame, an extension frame extensible from the main frame, a resilient support in the main frame, the extension frame when in extended position being supported near one edge by an edge of the resilient support, an auxiliary cushion adapted to overlie the extension frame when the extension frame overlies the main frame and to overlie the resilient support when the extension frame is extended, and means for adjusting the position of the resilient support in the main frame, to provide various positions of the seat when the extension frame is extended, comprising means forming notched slots, and pins receivable in the notches, said extension frame being slideable upon said main frame to retracted position in which it overlies and is supported by said resilient support.

FRED E. MOORE.
